2,488,717

MAGNETIZABLE WIRE RECORDING SYSTEM
AND METHODStanley D. Eilenberger, Kenosha, Wis., assignor,
by mesne assignments, to Chicago Coin Ma-
chine Co., a corporation of Illinois

Application November 19, 1945, Serial No. 629,566

3 Claims. (Cl. 179—100.2)

1

This invention relates to magnetic recording and reproducing and, in particular, to magnetic head design for recording or reproduction with a magnetic sound carrier in the form of a free wire wound on a circular drum, where such free wire passes through or by the magnetic recording or reproducing head. In part, the principles are the same as disclosed in my co-pending applications entitled, "Rectilinear pole piece for wire recording," filed May 9, 1945, Serial Number 592,811, now abandoned, and "Rectilinear pole piece," filed May 19, 1945, Serial Number 594,680, now U. S. Patent No. 2,433,207, granted Dec. 23, 1947; and reference should be made to these co-pending applications for a better understanding of the present invention.

For the purpose of this application, a rectilinear pole piece is defined as one having a thickness on the order of sound track diameter, a relatively long width in the direction of sound track travel and a height in accordance with coil design. In particular, this definition has been applied to a T-shaped pole piece where the head of the inverted T is in magnetic relation to the sound tracks. The operational principles of such a pole piece have been described in detail in the above-cited co-pending applications and, for the purposes of the present invention, it may simply be stated that such a pole piece is relatively independent of high frequency cut-off as a function of sound track speed, thus making possible relatively slow sound track speeds for a given high frequency response.

The present invention is similar to one of the co-pending applications above cited entitled, "Rectilinear pole piece for wire recording," filed May 9, 1945, Serial Number 592,811, now abandoned, in general form, but certain improvements have been made which result in a radical improvement in efficiency and the signal to noise ratio. Considering efficiency in terms of the output level of the magnetic head during the reproducing cycle, the gain in efficiency of a system operating according to the present invention over a system operated according to my previously cited co-pending application is on the order of 50 db., and this radical improvement in efficiency results in a greatly improved signal to noise ratio.

The signal to noise ratio is generally defined as the ratio of the signal voltage to the noise voltage, and in the present instance, the noise level remains essentially constant, if compared to the system described by my previously cited co-pending application, while the signal level is approximately 50 db., thus resulting in a 50 db. improvement in signal to noise ratio.

2

By way of further clarification, it may be briefly stated that the output level of the magnetic head operated in accordance with my previously cited co-pending application was on the order of microphone output level, which may be taken as —50 db., while the output of a head operated in accordance with the present invention is on the order of pick up level or approximately zero db.

A further feature of the present invention is that the fidelity is greatly improved over the system disclosed by my previously cited co-pending application, as will be shown farther below.

The objects of this invention are:

1. To provide a magnetic recording/reproducing system which shall be relatively free from the limitations of finite pole piece dimension and sound track speed as a function of high frequency response, to provide relatively good high frequency response at relatively low sound track speeds.
2. To provide a magnetic recording/reproducing system which shall operate at relatively high efficiency as compared to previously known systems.
3. To provide a magnetic recording/reproducing system which shall have a favorable signal to noise ratio as compared to previously known systems.
4. To provide a magnetic recording/reproducing system which shall essentially reproduce the recorded wave form with a minimum of frequency response correction to provide a relatively high fidelity system.

This invention will be best understood from a consideration of the following detailed description, in view of the accompanying drawings forming a part of the specification; nevertheless, it is understood that the invention is not confined to the disclosure, being susceptible to such changes and modifications as define no material departure from the salient features of the invention as expressed in the appended claims.

In the drawings:

Figure 1 represents a schematic view of a magnetizable-wire recording/reproducing system operated in accordance with my previously cited co-pending application, entitled "Rectilinear pole piece for wire recording," and all reference numerals are the same as in Figure 1 of this co-pending application, this drawing being included for reference purposes only.

Figure 1a is a cross section schematic view of Figure 1 through line XX, and is again identical with Figure 2 of my co-pending application cited just above.

Figure 2 represents a simplified view of the magnetic field associated with the pole piece the same as in Figure 1.

Figure 3 shows a modification of part of Figure 1, where the sound track position is in accordance with this invention, all other components being the same as in Figure 1.

Figure 4 represents a simplified field configuration for the sound track position of Figure 3.

Figure 5 is a grossly exaggerated section of sound track with a grossly exaggerated and simplified magnetic field configuration as it appears to the sound track passing by the pole pieces in Figure 3.

Figure 6 represents a modified pole piece shape for use in the arrangement of Figure 3.

Figure 7 represents a farther modified pole piece shape for use in the pole piece arrangement of Figure 3, and is the preferred form.

Figure 8 represents a modification of Figure 3 incorporating the pole piece shape illustrated by Figure 7, wherein both pole pieces are formed as a unit section.

Figure 9 is similar to Figure 8, except that the pole pieces are formed in two sections with a magnetic joint to facilitate construction of a complete recording/reproducing head, and this arrangement represents the preferred form.

Referring now to Figure 1, the magnetizable sound track is represented by 1, sound track 1 being wound from wire reel 2 onto wire reel 3 in the direction of motion as indicated by the arrows, for the recording of reproducing cycle, it being understood that the wire may be rewound from reel 3 onto reel 2 and that during the rewinding process the direction of motion will be opposite that shown by the arrows. The recording or reproducing pole pieces are represented by 4 and 5, having coils 6 and 7 associated therewith, said coils being connected in series aiding and having leads brought out to terminals 8, it being understood that terminals 8 are connected to a suitable recording or reproducing amplifier.

The novel feature of pole pieces 4 and 5 is that the dimension in the direction of sound track travel is on the order of or greater than the lowest frequency it is desired to record. This is in total disagreement with the previous conception of magnetic recording, where it had generally been accepted that, in order to carry out the recording/reproduction process, it was necessary to have a finite dimension in the direction of sound track travel on the order of one-half wave length of the highest frequency it was desired to record, thus necessitating an exceedingly small dimension, usually on the order of .001". The operational principle for rectilinear pole pieces, as represented by 4 and 5, has been more fully disclosed in my co-pending application hereinbefore referred to, but it may be briefly stated that pole pieces 4 and 5 should have a dimension Z at least equivalent to a full cycle of the lowest frequency it is intended to record, and preferably a dimension Z on the order of two cycles of the lowest frequency it is intended to record, where dimension is a function of frequency and sound track speed. It has been experimentally determined that a practical dimension for Z is on the order of $\frac{3}{8}$ " to $\frac{1}{2}$ ". A dimension smaller than $\frac{3}{8}$ " fails to fulfill the requirements of a system operated in accordance with this invention, and a dimension much greater than $\frac{1}{2}$ ", while theoretically sound, operates at low efficiency due to the relatively large mass of pole piece material. Obliteration is carried out by

obliteration pole piece 9 and its associated obliteration coil 10, having terminals 11 connected to a suitable source of obliterating current, which is usually a source of D. C. voltage, the magnitude of which is determined by obliteration head design. Air gaps 12 and 13 are shown between sound track 1 and pole pieces 4 and 5.

Referring now to Figure 1a, a cross section view of Figure 1 is shown through the line XX, all reference numerals being the same as in Figure 1. The dimension V of pole pieces 4 and 5 is non-critical and may be equal to or greater than the diameter of sound track 1. For reasons of mechanical conveniences dimension V is usually made much greater than the diameter of sound track 1. For example, assuming that sound track 1 has a diameter on the order of .004", then it would be satisfactory to make dimension V of pole pieces 4 and 5 on the order of $\frac{1}{16}$ ", thus removing the necessity for extremely accurate guiding means.

It is understood that Figures 1 and 1a are included in this specification for reference purposes only, and do not disclose the novel features of this invention, such novel features being represented by Figures 2 through 9 inclusive.

Referring now to Figure 2, a partial view of pole pieces 4 and 5 is shown, and it may be assumed at a given instant, pole piece 4 represents a north pole and pole piece 5 represents a south pole, and that pole pieces 4 and 5 are unit poles, so that the lines 14 would represent the normal path of the transverse magnetic flux, it being understood that this picture is over simplified, as in actual practice the magnetic flux lines will not be exactly straight, and that in a dynamic system there will be leakage flux at both the leading and trailing edges, but for the purpose of this invention, it introduces no error to assume the flux lines are straight and to ignore the leakage flux known to exist at the leading and trailing edges of the pole pieces.

Referring now to Figure 3, the conditions are essentially the same as in Figure 1, except that sound track 1 has been made to pass obliquely between pole pieces 4 and 5, so as to be in relatively close magnetic relation to pole piece 4 at leading edge A and also to be in relatively close magnetic relation to trailing edge D of pole piece 5, at the same time maintaining relatively distant magnetic relation to trailing edge B of pole piece 4 and leading edge C of pole piece 5. As a matter of physical practice, it has been found satisfactory to allow sound track 1 to travel obliquely between pole pieces 4 and 5 in magnetic contact with pole piece 4 at point A and pole piece 5 at point D. This arrangement does not result in undue pole piece wear, the wear being taken up by guides normally associated with any wire recording system. As a matter of mechanical convenience and improved performance, dimension Y is now made relatively great in comparison to the diameter of sound track 1. For example, assuming that sound track 1 has a diameter on the order of .004", it has been experimentally determined that a practical dimension for Y would be on the order of .025", which would give an air gap on the lines BD and AC of .025" minus .004" or .021", with air gaps between sound track 1 and point A and D approximating zero. The dimension Y is variable within limits, the lower of which is critical at twice sound track diameter, or in the example as given, at approximately .008". The upper limit is less critical and desirable results have

been obtained with this dimension in excess of ten times sound track diameter or, in the example as given, in excess of .050".

Referring now to Figure 4, a simplified picture of the flux path is shown, where we may again assume that at a given instant, pole piece 4 is a unit north pole and pole piece 5 is a unit south pole, and that flux lines 14 result from this condition, thus producing, to some degree, transverse polarization of sound track 1. At the same instant, we have a closed magnetic circuit between points A and D, so that there is produced longitudinal polarization of sound track 1, as represented by the flux path 15.

Referring now to Figure 5, the condition illustrated by Figure 4 is exaggerated, 1a representing a section of the sound track 1, where joint AA is the instantaneous north pole and point DD the instantaneous south pole, with flux lines 14a representing the transverse polarization of sound track 1a, and flux lines 15a representing the longitudinal polarization of sound track 1a, it being understood that these flux lines will not be perfectly straight as represented in Figure 5, and this is particularly so in a dynamic system where sound track 1a is moving in respect to its associated pole pieces, thus bending flux lines 14a to a degree partly determined by the speed of sound track 1a in respect to its associated pole pieces. However, it is believed, that flux path 15a will be largely confined to the sound track due to the relatively low reluctance of a closed magnetic path.

Referring now to Figure 6, a modified pole piece structure is shown in the form of a T, having a pole piece face 16 and coil 17 associated with pole piece body 18 and connected to a suitable recording/reproducing amplifier at terminals 8. While the pole piece illustrated by Figure 6 may assume various modified forms, it has been experimentally determined that practical dimensions would be pole piece body width W equal $\frac{1}{8}$ " and pole piece face width Z equal $\frac{1}{2}$ ", the practical thickness for such a pole piece being on the order of .025" and the length of pole piece body 18 being determined by coil design.

Referring now to Figure 7, a farther modification of pole piece design is represented, where pole piece face 19 is shown with triangular leading and trailing edges, all other conditions being the same as represented by Figure 6.

Referring now to Figure 8, a complete schematic view of a recording/producing head is shown, where pole piece 22 has faces 24A shaped in accordance with Figure 7 and coil 23 connected to a suitable recording/reproducing system at terminal 8, the design being such that guiding means normally associated with sound track 1 causes said sound track to move obliquely between pole piece faces 24A in accordance with Figure 3.

Referring now to Figure 9, a modification of Figure 8 is shown, where pole pieces 25 and 26 are two separate pieces mechanically, having pole piece faces 27A and 28A and a magnetic joint at 29, where said magnetic joint 29 may be either a butt joint or lap joint, but 29 is intended to represent a closed magnetic circuit without introducing an air gap. This is the preferred design, as the two piece construction allows easier assembly of a complete recording/reproducing head, and in practice it has been found satisfactory to allow pole pieces 25 and 26 to over lap each other about $\frac{1}{8}$ " inside of the coil associated with pole pieces 25 and 26.

Any of the high permeability alloys such as mu-metal or Permalloy, have been found satisfactory as pole piece material, the mechanical design being a function of good engineering practice.

The present system disclosed by this invention, differs from the system disclosed by my previously mentioned co-pending applications, in the method of passing the sound track through the head, and the results obtained may be briefly summarized as follows:

The output level for a constant amplitude recording is approximately 50 db. higher for a system operated in accordance with Figure 3 as compared to a system operated in accordance with Figure 1.

The signal to noise ratio is also approximately 50 db. better for the system of Figure 3 over the system of Figure 1.

The fidelity is much better in that the arrangement of Figure 1 tends to distort the lower frequencies, where such lower frequencies approximate a full wave length as a function of pole piece dimension and sound track speed and also tends to distort the even harmonics of this fundamental frequency. This distortion is absent in a system operated according to Figure 3 and lower frequencies are produced with a fidelity equivalent to the high frequency fidelity, the high frequency fidelity being good for both systems.

The reason for this is not entirely known. It is not a function of the closed magnetic circuit as compared to an open magnetic circuit. For example, in a system operated in accordance with Figure 1, all magnetic dimensions may be closely adjusted to provide a closed magnetic circuit with a result that the system is essentially inoperative. It is believed that the combination of transverse polarization and longitudinal polarization produces a result not obtainable with either polarization alone and this is in accordance with recent magnetic theory. For example, assuming that we record a single frequency of 5,000 C. P. S., we will record a great number of transverse magnets in sound track 1 and simultaneously a number of longitudinal magnets in sound track 1. These cross magnets interfere with each other to a degree not yet determined, but the end result is a longitudinal polarization, where the trailing edge of the pole piece face acts as an infinitely fine point. The details of this process have been fully explained by one of my co-pending applications previously cited entitled "Rectilinear pole piece". In certain recently developed magnetic devices, auxiliary means are used to superpose a second frequency on the sound track in addition to the recorded frequency and such systems have been tentatively explained as producing better fidelity at higher efficiency due to the presence of many minor descending loops in the hysteresis loop, and it is believed that the present invention accomplishes the same end result by a simpler means, and that the cross polarization produces numerous minor descending loops in comparison to the normal hysteresis loop, thus resulting in a longer and straighter descending limb, which may be used for recording. In addition to these advantages, the present system includes all of the advantages offered by the rectilinear process, as set out by my previously mentioned co-pending applications, in that good high frequency response is obtained at relatively low sound track speeds.

The above examples are for the purpose of illustrating some of the methods and means by which the broad purposes of this invention may be carried out and are not to be deemed as restrictive in any manner. Other modifications and alternatives will occur to those skilled in the art without departing from the scope of this invention as defined by the following claims.

Having thus described the invention, what is claimed as new is:

1. In a magnetic system of the type having a sound track transversely magnetized for recording and reproducing complex sound waves covering a broad range of frequencies, a recording and reproducing head providing spaced magnetic pole faces transversely aligned on opposite sides of the track having a dimension along the path of sound track travel of the order of the speed of the sound track divided by the lowest frequency to be recorded and means for moving a sound track obliquely through the normal flux path between the pole faces.

2. The system of claim 1 wherein said sound track is in magnetic engagement with the lead-

ing edge of one pole face and the trailing edge of the other pole face.

3. The system of claim 1 wherein the distance between opposed pole faces is in excess of twice the transverse dimension of the sound track.

STANLEY D. EILENBERGER.
